UNITED STATES PATENT OFFICE

WALTER EVERETT MOLINS, OF DEPTFORD, LONDON, ENGLAND

CIGARETTE CONTAINER

Application filed September 17, 1927, Serial No. 220,166, and in Great Britain October 28, 1926.

This invention is for improvements in or relating to cigarette containers, and more particularly to cigarette containers of the type wherein a single row of cigarettes is located within a pocket with the ends thereof directed towards the mouth of the same, and it has for its object the provision of means whereby cigarettes may be retained against unintentional displacement in the said pocket 10 after some of the cigarettes have been removed therefrom.

It is well known that with cigarette containers of the slide and shell type, that the cigarettes are liable to shake about in the 15 container to the detriment of the cigarettes after one or more cigarettes have been removed from the container.

The present invention consists of a cigarette packet having a U or equivalently shaped portion arranged to receive a single row of cigarettes with their axes directed towards the open end of the packet, characterized by the provision of a series of scallops in the said U shaped portion each arranged to partly 25 envelop a cigarette, in such a manner that the free ends of the scallops lie in the depressions between adjacent cigarettes.

Further, the present invention consists of a cigarette container as set forth in the preceding 30 paragraph, wherein two sets of scallops are arranged to engage with the cigarettes for the purpose hereinafter set forth.

The invention is more particularly described with reference to the accompanying 35 drawings, in which:—

Fig. 1 illustrates one packet constructed according to the present invention.

Fig. 2 is a modified form of packet to that 40 illustrated in Fig. 1.

Fig. 3 illustrates a double pocket container embodying the subject matter of the present invention.

Figs. 4 and 5 are modified forms of the packet illustrated in Fig. 3, and

Fig. 6 illustrates a slide and shell packet 45 wherein the slide embodies the subject matter of the present invention.

Referring to the drawings, Fig. 1 shows a single pocket container arranged to accommodate ten cigarettes and furnished with a

series of scallops 1 which are adapted to be depressed to that each scallop is arranged to partly encircle a cigarette. In the example illustrated, the extension flap 2 is provided with a scalloped edge 3 which corresponds with the scallops 1. The scallops 3 are produced during the manufacture of the blanks from which the packets are formed. The blanks are cut from a web, so that the scalloped edge 3 is formed simultaneously with the scallops 1 of the blank of the preceding packet. If necessary, an additional set of scallops 4 may be made at a point along the length of the blank in order to hold the cigarettes at two points around their lengths, and thus form additional security against displacement. The rear broad panel of the packet is preferably slit at 5 so that the closure flap 2 may be folded down so as to permit the end of each cigarette to be easily taken from the packet.

Fig. 2 illustrates a modified form of the packet illustrated in Fig. 1. The scallops 6 are formed substantially at the mid-length of the front panel in order to support each cigarette at the mid-length thereof, and in addition, provides a straight edge along the mouth of the packet which ensures that the edge of the extension flap is also straight where the blanks are cut from a web.

Fig. 3 shows a double pocket container provided with scallops similar to those illustrated in Fig. 1. A packet of this character may be formed in one piece or made in the form of two single packets joined together.

Fig. 4 illustrates a modified form of packet to that illustrated in Fig. 3 but in this case, the packet is lined with tin foil or similar material, and an aperture is provided arranged to show a trade mark or monogram 50 impressed upon the foil liner.

Fig. 5 shows a section of Fig. 4 from which it will be seen that the centre portion of the foil strip 7 which is located in proximity to the closure flap of the packet is provided with a tuck 9 which, when the packet is in the extended condition, is located at right angles to the extension flap and forms an abutment for the cigarettes of one pocket when the packet is held so as to allow the cigarettes of

one pocket to slide from the same under the force of gravity.

When the two pockets are folded one upon the other the tuck 9 is located between the free ends of the two rows of cigarettes and so prevents one row of cigarettes from coming into contact with the other.

Fig. 6 shows the invention applied to a slide of a slide and shell packet. In the case 10 illustrated, the scallops are formed on one end flap, but it is to be understood that the scallops may be provided on both end flaps, if necessary.

It is found in forming the containers other 15 than slide and shell packets of the character hereinbefore set forth, that with containers adapted to hold ten cigarettes, less material is required than is necessary to make a slide and shell packet of the same capacity, where- 20 as in the case of a container adapted to accommodate twenty cigarettes no more material than is required for a slide and shell container is necessary.

It will be appreciated that the container 25 may be first formed and the cigarettes there- after inserted and the sides of the container either sealed by hand or automatically. On the other hand, the container may be formed, filled and sealed entirely by automatic means.

30 What I claim as my invention and desire to secure by Letters Patent is:—

1. A cigarette container constructed from an integral blank of sheet material and comprising a pair of open ended pockets, each 35 adapted to hold a single row of cigarettes, and a flap hingedly connecting the two pockets together so that they may be opened out into line with their open ends directed toward one another and adapted to extend 40 across the open ends of the pockets when the latter are folded one upon the other to completely enclose the cigarettes, each of said pockets being provided with a serrated portion integral with the pocket and extending 45 within the pocket for engagement in the interstices between adjacent cigarettes, whereby the latter may be retained against unintentional displacement.

2. A cigarette container comprising a pair 50 of open ended pockets, each adapted to hold a single row of cigarettes, and a flap for hinging the two pockets together so that they may be opened out into line with their open ends directed toward one another and adapted 55 to extend across the open ends of the pockets when the latter are folded one upon the other, said pockets and flap being integrally formed and consisting of an outer covering of fibrous material and an inner 60 wrapper of foil, the flap portion of said wrapper being provided with an upstanding fold forming an abutment for engagement by the cigarettes when said pockets are opened.

3. A cigarette container constructed from 65 an integral blank of sheet material and com-

prising a pair of open ended pockets, each adapted to hold a single row of cigarettes, and a flap for hinging the two pockets together so that they may be opened out into line with their open ends directed toward one another and adapted to extend across the open ends of the pockets when the latter are folded one upon the other, said pockets and flap being integrally formed and consisting of an outer covering of fibrous material and an inner wrapper of foil, the flap portion of said container being provided with an upstanding fold forming an abutment for engagement by the cigarettes when said pockets are opened, each of said pockets being provided with a serrated portion, the teeth of which are deflected to engage between adjacent cigarettes to retain the latter against unintentional displacement.

4. A cigarette container comprising a pair 85 of open ended pockets, each adapted to hold a single row of cigarettes, and a flap for hinging the two pockets together so that they may be opened out into line with their open 90 ends directed toward one another and adapted to extend across the open ends of the pockets when the latter are folded one upon the other, a strip of foil extending within each pocket and across the flap, that portion of the foil adjacent the flap extending outwardly from the flap to form an abutment 95 for engagement by the cigarettes when said pockets are opened.

5. A cigarette container constructed from an integral blank of sheet material and comprising a pair of open ended pockets, each adapted to hold a single row of cigarettes with the axes directed toward the mouth of each pocket, and a flap hingedly connecting the two pockets together so that they may be opened out into line with their mouths 100 directed toward one another, the said flap being adapted to extend across the mouths of the pockets when the latter are folded one upon the other with the front broad panels 105 of the pockets abutting to completely enclose the cigarettes, the edge of the broad front panel of each pocket defining the mouth of the pocket being serrated to provide a plurality of tongues extending within the pocket 110 at the mouth for engagement in the interstices between adjacent cigarettes, whereby the latter may be retained against unintentional lateral displacement within the pocket.

In testimony whereof I hereunto affix my 115 signature.

WALTER EVERETT MOLINS.
